(57) **CLAIM**

The ornamental design for a bouquet jewel, as shown and described.

DESCRIPTION

FIG. 1 is a perspective view of a plurality of bouquet jewels of the present invention, shown in use with a bouquet of flowers.

FIG. 2 is a perspective view of a bouquet jewel of the present invention.

FIG. 3 is a side view of the bouquet jewel of FIG. 2; and, FIG. 4 is a top view of the bouquet jewel of FIG. 2. The broken lines showing of a flower bouquet and second gem setting in use is for illustrative purposes only and forms no part of the claimed design.
